PARABOLIC SOUND REFLECTING MICROPHONE HOLDER

Daniel Armstrong Gibson, Toronto, Ontario, Canada,
assignor to Dan Gibson Productions Ltd., Toronto,
Ontario, Canada

Filed June 12, 1970, Ser. No. 33,458

Claims priority, application Canada Apr. 9, 1970

Term of patent 7 years

Int. Cl. D14—01

U.S. Cl. D26—14

FIG. 2

FIG. 1

FIG. 3

FIG. 1 is a perspective view of a parabolic sound reflecting microphone holder taken from the concave side of the parabolic member;

FIG. 2 is a perspective view of the device of FIG. 1 taken from the convex side of the parabolic member; and

FIG. 3 is a side elevation view of the device of FIGS. 1 and 2.

I claim:

The ornamental design for a parabolic sound reflecting microphone holder, as shown and described.
